UNITED STATES PATENT OFFICE.

DANIEL A. DILLMAN, OF OREGON CITY, OREGON.

PULP-FEEDER FOR PAPER-MAKING MACHINES.

1,166,042.

Specification of Letters Patent. Patented Dec. 28, 1915.

Application filed March 6, 1915. Serial No. 12,609.

To all whom it may concern:

Be it known that I, DANIEL A. DILLMAN, a citizen of the United States, residing at Oregon City, in the county of Clackamas and State of Oregon, have invented certain new and useful Improvements in Pulp-Feeders for Paper-Making Machines, of which the following is a specification.

In the manufacture of paper the pulp is generally fed to the machine from what is commercially known as a stuff-box. This stuff-box is subdivided into three compartments which are in communication with one another and with the paper machine and the source of supply of the pulp stock. In the operation of paper machines supplied with pulp from a stuff-box the thickness of the paper varies which is due chiefly to the unequal feed which in turn is attributable to the variation in the density of the pulp.

The present invention has for its object to insure the production of paper of uniform thickness and to automatically control the feed of the pulp to the paper making machine, such feed being automatically controlled by the variation in the change of level of the pulp in one of the compartments of the stuff-box.

A further purpose of the invention is the provision of means which may be set according to the nature of the work and which after being set operates automatically to control the delivery of the pulp to the paper making machine so as to insure the production of paper of uniform thickness.

With these and other objects in view, which will readily appear as the nature of the invention is better understood, the same consists in the improved construction and novel arrangement and combination of parts which will be hereinafter fully described and particularly claimed.

In the accompanying drawings has been illustrated a simple and preferred form of the invention, it being, however, understood that no limitation is necessarily made to the precise structural details therein exhibited, but that changes, alterations and modifications within the scope of the invention as claimed may be resorted to when desired.

Referring to the drawings:—Figure 1 is a perspective view of a stuff-box such as generally used for feeding pulp to a paper making machine, such box being provided

with means embodying the invention, parts being broken away to show more clearly the relation of the operating elements. Fig. 2 is a longitudinal section through the receiving and overflow compartments of the box on the line 2—2 of Fig. 1 looking in the direction of the arrows; Fig. 3 is a transverse section through the receiving and feeding compartments of the box on the line 3—3 of Fig. 1 looking in the direction of the arrows; Fig. 4 is a horizontal section on the line 4—4 of Fig. 1. Fig. 5 is a view of details of the attachments for gate N.

Corresponding and like parts are referred to in the following description and indicated in all the views of the drawings by the same reference characters.

The box in its general formation is of ordinary construction, such as usually provided for feeding pulp stock to a paper making machine. The box comprises three compartments A, B and C. A pipe D communicates with the bottom of the compartment A and connects with a source of supply of the pulp. A pipe E connects with the bottom of the compartment C and likewise connects with the source from which the pulp is supplied. A pipe F connects with the bottom of the compartment B and serves to convey the pulp in measured quantity to the paper making machine. The pulp is supplied to the receiving compartment A and passes therefrom to the feeding compartment B through an opening 1 formed in the lower portion of the partition 2 separating the compartment A from the compartment B. A gate H is adapted to close the opening 1 and may be opened to a greater or less extent to regulate the flow of the pulp from the compartment A into the compartment B. A stem 3 extending upward from the gate H is threaded at its upper end and receives an adjusting nut 100 J by means of which the gate is opened more or less and held in the adjusted position. The partition 4 separating the compartment A from the compartment C terminates a short distance from the upper edge of the partition 2, thereby providing for an overflow of surplus pulp from the compartment A into the compartment C, such surplus pulp returning through the pipe E to the source of supply.

In accordance with the present invention a by-pass R connects the lower portion of

the feeding compartment B with the lower portion of the overflow compartment C. Ordinarily the overflow compartment C is in line with the receiving compartment A and to one side of the feeding compartment B. As a result of this arrangement an angular space is formed between the adjacent walls of the compartments B and C. The by-pass R extends across this angular space and any surplus pulp passing into the feeding compartment B is discharged therefrom through the by-pass R into the overflow compartment C. A gate N controls the by-pass R and is preferably arranged within the compartment B close to the side with which the by-pass connects. A rim 5 surrounds the opening formed in the side of the compartment in line with the by-pass R and extends a short distance into the compartment and the gate N is seated against such rim and is spaced from the adjacent wall of the compartment thereby. The gate N has a stem 6 which is adjustably connected at its upper end with a lever 7, the latter being mounted upon a standard L and provided upon its opposite end with a float K. An adjusting nut M threaded upon the end of the stem 6 serves to adjustably connect the gate with the lever 7.

30 A nozzle 8 is arranged to deliver a jet of water into the space formed between the gate N and the adjacent wall of the compartment B to prevent pulp collecting in the rear of the gate and interfering with its free movements.

35 A collar G is fitted to the upper end of the pipe F and may be adjusted vertically to any determinate height with reference to the receiving end of the by-pass R so that it may be set to regulate the feed of the pulp to the paper making machine. The collar G may be held in place by friction or in any manner to insure its retaining the position to which it may be adjusted.

40 45 The float K may be of any construction and is disposed above the receiving compartment A so as to be acted upon by the pulp therein. As the level of the pulp in the receiving compartment A changes according to the supply and delivery the float K correspondingly rises or falls and through the lever 7 and stem 6 imparts a corresponding movement to the gate N, thereby regulating the receiving opening of the by-pass R and controlling the discharge of the surplus pulp from the feeding compartment B into the overflow compartment C. By moving the float upon the lever 7 or changing the fulcrum of such lever the movement of the gate N may be regulated.

50 55 In the operation of the stuff-box the pulp enters the receiving compartment A by way of the pipe D and passes into the feeding compartment B through the opening 1 thence to the paper machine through the

60 pipe F. The gate H is set so that the pulp enters the compartment A faster than it leaves such compartment through the opening 1 and as a result the compartment A soon fills and overflows into the compartment C the surplus pulp returning to the source of supply through the pipe E. When the density of the pulp varies from any cause the level of the pulp in the compartment A rises or falls, thereby causing a 70 corresponding movement of the float K and which movement is transmitted to the gate N through the connections 6 and 7. When the level of the pulp in the tank A rises thereby causing a greater amount of pulp 75 to pass through the opening 1 into the compartment B the gate N is lowered by the rising of the float K, thereby permitting more pulp to pass from the feeding compartment D through the by-pass R into the overflow compartment C, such increase in the overflow being proportionate to the additional supply with the result that the feed of pulp to the paper making machine is practically uniform, thereby insuring the 80 production of paper of even thickness.

85 The float K is preferably hollow and of cylindrical form and is adapted to receive a liquid which changes its level according to the relative position of the float with the 90 result that the effective weight varies according to the inclination of the float and the level of the pulp. When the pulp is medium the weight of the liquid in the float is uniformly distributed. When the pulp 95 is thick or dense the excess of liquid occupies a position at the inner end of the float and when the pulp is thin or extremely fluid the bulk of the liquid is located at the outer end of the float. This mobile fluid weight 100 results in a nicely and automatic adjustment of the float according to the consistency of the pulp with the result that the regulator is rendered more sensitive in operation.

105 110 The gate N is retained in place and directed in its movements by means of a stem 10 and a guide 11, the latter being secured to the inner face of the wall of the compartment B with which the by-pass R connects. The stem 10 of the gate N operates in the guide 11.

115 Having thus described the invention what is claimed as new is:—

120 125 130 135 1. A stuff-box for feeding pulp to paper making machines, the same comprising a compartment for receiving the pulp, a compartment for feeding the pulp and receiving the pulp in regulated quantity from the receiving compartment, an overflow compartment receiving the surplus pulp from the receiving compartment, a by-pass connecting the feeding compartment with the overflow compartment, and means actuated by the change of level of the overflow pulp

- from the receiving compartment into the overflow compartment for regulating the discharge of surplus pulp from the feeding compartment through the by-pass into the 5 overflow compartment.
2. A stuff-box for supplying pulp to paper making machinery, such stuff-box comprising receiving, feeding and overflow compartments, the receiving and feeding compartments having a regulable intercommunication, a by-pass connecting the lower portions of the feeding and overflow compartments, a gate for controlling the discharge of surplus pulp from the feeding compartment into the by-pass and a float connected with such gate for controlling the movements thereof and adapted to be actuated by the change of level of the overflow from the receiving compartment into the overflow 15 compartment.
3. A stuff-box for regulating the supply of pulp to paper making machinery, the same comprising a plurality of intercommunicating compartments, the one receiving the pulp from a suitable source of supply, another having regulable communication with the receiving compartment and having a pipe leading therefrom to the machine to be supplied and the third compartment receiving the overflow from the receiving and feeding compartments, a collar having adjustable connection with the receiving end of the feed pipe leading from the feeding compartment, a by-pass connecting the feeding and overflow compartments, and means for regulating the outlet from the feeding compartment into the by-pass be- 20 25 30 35
- tween the feeding and overflow compartments and adapted to be actuated by the change of level of the overflow pulp in the receiving compartment.
4. In a stuff-box for paper making machinery comprising a plurality of intercommunicating compartments, one receiving the pulp, the other feeding the same in proper quantity to the machine and the third having the overflow from the receiving compartment discharged therein, a by-pass connecting the feeding compartment with the overflow compartment, a rim projecting into the feeding compartment in line with the by-pass, a gate for controlling the by-pass and engaging the said rim and spaced thereby from the adjacent wall of the feeding compartment and a float arranged to operate in the receiving compartment and having connection with the said gate.
5. A stuff-box for supplying pulp to paper making machinery, the same comprising a feeding compartment, a pipe leading from the feeding compartment to convey the pulp to the paper making machine, a collar having adjustable connection with the said pipe, an overflow pipe leading from the feeding compartment, and means for regulating the discharge of surplus pulp into the overflow and adapted to be regulated by the change of level of the pulp.

In testimony whereof I affix my signature in presence of two witnesses.
